ENGINE

David J. Dolan, Cleveland Heights, Ohio

Application August 7, 1936, Serial No. 94,814

15 Claims. (Cl. 123—50)

This invention relates to internal combustion engines and more particularly to a type of engine adapted for location within the wing of an aeroplane for propulsion of the latter.

An object of the invention is to provide an engine of flat form for the purpose. Another object is to provide improved and simplified supercharging and scavenging effect upon the engine combustion chambers. Another object is to provide cooperative structural effect between engine and wing.

Further objects are to provide novel and improved details of the engine structure as will appear.

15 The exact nature of this invention together with further objects and advantages thereof will be apparent from the following description taken in connection with the accompanying drawings, in which Figs. 1 and 2 are horizontal and longitudinal sections respectively, illustrating in conventional manner the engine and its relation with immediately associated aeroplane parts, the plane of Fig. 1 being indicated by the line 1—1, Fig. 2, and the plane of Fig. 2 being indicated by the line 2—2; Fig. 1; Fig. 3 is an enlarged detail of typical parts of the engine taken as in the plane of line 3—3; Fig. 1, and having parts broken away to show details of construction.

With reference now to the drawings, 1 is the crankshaft of the engine which has suitable bearings in a crankcase 2, which is disposed fore and aft of an aeroplane wing generally designated by the reference character 3 and extends forward of the latter and there carries the usual propeller 4. 20 For driving the crankshaft 1, the engine has a number of stationary pistons 5 on which cylinders 6 are movable.

The engine illustrated has thirty-two cylinders, all disposed within the wing, sixteen on each side 25 of the crankshaft. For each crank there are two parallel lines of cylinders, one above the other on axes transverse of the plane, each line having four coaxial cylinders, two on each side of the crank, and the eight cylinders of such two lines 30 comprising a set effective upon one of the cranks of the crankshaft as will appear. The shaft having four cranks, there are four such sets of eight cylinders, comprising a total of thirty-two.

With reference now particularly to Fig. 3 which 35 illustrates the characteristics of a set of cylinders for driving one of the cranks 1a, 1 is a manifold arranged generally to extend fore and aft of the wing, having an associated flange part 1a extending to the upper and lower extremities of the wing 40 to serve as a bulkhead for the latter, and joining

transverse bulkheads 7b at its forward and rearward extremities.

The manifold 1 is generally hollow and the pistons 5 are mounted thereon in aligned pairs, the pistons being hollow and their cavities communicating with that of the manifold 1 as illustrated particularly in Figs. 2 and 3.

A cylinder 6 is provided for each piston 5, but means are provided for support of the cylinders independent of their pistons. Thus for each line of cylinders a rod 8 is provided having bearing in bosses 2a in the crankcase 2, 7c in the manifold 1, and at 8a in a bulkhead 9, one at each lateral extremity of the engine. These bulkheads 9 extend between the bulkheads 7b and thus cooperate with the latter to substantially enclose the engine as well as reinforce the wing. Each rod 8 is disposed adjacent its line of cylinders with each of which it is secured as by stops 8b so that these cylinders are constrained to move in unison on their pistons and have support from their rod.

Of each line of cylinders the pair adjacent the crankshaft are directly interconnected by a rod 10 interconnecting their head portions as indicated in Fig. 3, such rod 10 having yieldable elements of 25 rubber or the like conventionally indicated at 10a.

The rods 10 extend through the crankcase 2, in the sides of which they have bearing, and for each set of cylinders its pair of rods 10 are interconnected by a crosshead having a pair of members 11 between which a guideway is provided for the corresponding crank, a block 1b being preferably provided upon the crank pin 1a for improved bearing in the crosshead. The arrangement will be recognized as generally similar to that known 35 as the Scotch yoke, and by which it will be apparent that reciprocation in unison of the eight cylinders of the set may cause rotation of the crankshaft.

Each piston 5 has a port 5a and each cylinder 6 40 a cooperative ported bypass 6a by which air may pass from the hollow of the piston into the combustion chamber of the cylinder in timed relation with the stroke of the cylinder on the piston—when the cylinder is adjacent the outer end of its 45 stroke. The cylinder also has an exhaust port 6b located opposite the described inlet bypass whereby products of combustion are released and assisted in exhaustion by the incoming air from the piston. The arrangement will be recognized as 50 generally a typical one for operation on the two-stroke cycle.

Each piston 5 is provided with a nozzle conventionally illustrated at 5b in its head end for injection of fuel into its combustion chamber. 55

The nozzles of parallel adjacent pistons of a set are served by common piping 12 whereby simultaneous injection is had for both combustion chambers, it being appreciated that the line 12 is served by a timed fuel injection pump as will be appreciated by one familiar with the art.

For leading off the exhaust gases a manifold 13 is provided for each row of cylinders, each cylinder of which is provided with a pipe 6c leading into

- 10 an opening in the near side of the manifold, such opening being elongated in the direction of the cylinder to accommodate the movement of the cylinder in its stroke. The forward end of each exhaust manifold has a mouth opening in the 15 forward part of the wing as illustrated in Figs. 1 and 2, and the rearward end is of course open also to the atmosphere. Thus during operation a stream of fresh air will be caused to flow through each exhaust manifold and will have ejector effect 20 upon the exhaust pipes leading thereto as well as cooling effect upon the exhaust gases.

The inlet manifolds 7 similarly have enlarged mouths 1d opening into the forward edge of the wing and the parts are so proportioned and arranged 25 that these inlet manifold mouths are in the slip stream of the propeller, that is, located adjacent the ends of the blades as indicated in Fig. 1. Thus, during operation, the inlet manifolds will be maintained full of air at a pressure 30 above atmosphere and supercharging effect will result. Each manifold serving sixteen cylinders and the latter including eight pairs acting together and upon a two-stroke cycle, and the propeller having four blades and being mounted 35 directly on the crankshaft, one blade will pass the mouth of the manifold for each charge of air withdrawn from the manifold. Thus the propeller may be so timed upon the shaft that the pulsations of pressure which it produces within 40 the manifold are peaked coincidentally with the demand upon the manifold, and a maximum supercharging effect had.

It is to be noted that whereas a set of eight cylinders are associated with each crank, and all 45 of these cylinders move in unison, yet four of them are in their compression stroke while the other four are in their combustion stroke. Thus the total pressure which the crosshead has to deliver to the crank, is only the difference between combustion and compression pressures, so 50 that the load upon the crosshead is minimized. Further, the resilient elements 18a serve to permit a limited yield at the time of maximum combustion pressure, thus still further reducing 55 the maximum stresses upon the crosshead.

What I claim is:

1. An engine for the purpose described comprising an aligned pair of stationary pistons, a cylinder for each piston, a crank adjacent the head end of one of said cylinders, means yieldably connecting said cylinder to said crank, and separate means rigidly interconnecting said cylinders.

2. An engine for the purpose described comprising an aligned pair of stationary hollow pistons, means interconnecting said pistons and providing air inlet to each, a cylinder for each piston, a crank adjacent the head end of one of said cylinders, means connecting said cylinder to said crank, means interconnecting said cylinders, each piston and cylinder having parts cooperative for timed admission of air from piston to cylinder.

3. An engine for the purpose described comprising a plurality of aligned pairs of stationary

pistons, manifold means interconnecting said pistons and providing air inlet to each, a cylinder for each piston, a crank adjacent the head ends of adjacent cylinders, means connecting said head ends to said crank, means connecting the aligned cylinders to each other, each cooperative piston and cylinder having parts cooperative for timed admission of air from piston to cylinder.

4. An engine for the purpose described comprising a plurality of aligned pairs of stationary pistons, manifold means interconnecting said pistons and providing air inlet to each, a cylinder for each piston, a crank adjacent the head ends of adjacent cylinders, means connecting said head ends to said crank, means connecting the aligned cylinders to each other, each cooperative piston and cylinder having parts cooperative for timed admission of air from piston to cylinder, said manifold means being arranged to comprise a bulkhead supporting said pistons and extending to the contour of the wing of an aeroplane.

5. An engine for the purpose described comprising a parallel pair of stationary pistons, a cylinder for each piston, a crank adjacent the head ends of said cylinders, means connecting said cylinders to said crank to cause said cylinders operating synchronously to actuate said crank, said pistons having fuel injection nozzles for their cylinders, and a common timed fuel feed for both said nozzles.

6. An engine for the purpose described comprising a parallel pair of stationary pistons, a cylinder for each piston, a crank adjacent the head ends of said cylinders, and means connecting said cylinders to said crank to cause said cylinders operating synchronously to actuate said crank and comprising a rod connected to each cylinder, and a crosshead interconnecting said rods and said crank and providing a guideway for said crank.

7. An engine for the purpose described comprising a parallel pair of stationary pistons, a cylinder for each piston, a crank adjacent the head ends of said cylinders, and means connecting said cylinders to said crank to cause said cylinders operating synchronously to actuate said crank and comprising a rod connected to each cylinder, and a crosshead interconnecting said rods and providing a guideway for said crank, said rods having elements providing yield between said cylinders and said crosshead.

8. An engine for the purpose described comprising a parallel pair of stationary pistons, a cylinder for each piston, a crank adjacent the head ends of said cylinders, and means connecting said cylinders to said crank to cause said cylinders operating synchronously to actuate said crank and comprising a rod connected to each cylinder, and a crosshead interconnecting said rods and providing a guideway for said crank, a crankcase for said crank, each said rod having a bearing in said crankcase.

9. An engine for the purpose described comprising a parallel pair of stationary pistons, a cylinder for each piston, a crank adjacent the head ends of said cylinders, and means connecting said cylinders to said crank to cause said cylinders operating synchronously to actuate said crank and comprising a rod connected to each cylinder, and a crosshead interconnecting said rods and providing a guideway for said crank, a crankcase for said crank, each said rod having a bearing in said crankcase on each side of said crosshead.

10. An engine for the purpose described comprising a plurality of stationary pistons horizontally disposed in spaced aligned relation, a cylinder for each piston, means interconnecting said cylinders to cause them to move in unison upon their pistons, and means supporting said cylinder interconnecting means, and thereby said cylinders, independent of said pistons.
- 5 11. In an aeroplane wing, an engine having a crankshaft extending fore and aft, a bulkhead, pistons secured to said bulkhead and disposed upon lateral axes, cylinders for said pistons, and means connecting said cylinders to said crankshaft.
- 10 12. In the wing of an aeroplane, an engine having a crankshaft extending fore and aft of said aeroplane, a fore-and-aft bulkhead having a passage, hollow pistons secured to said bulkhead and disposed upon lateral axes, with the passage of said bulkhead communicating with the cavities of said pistons, a cylinder for each piston, said pistons and cylinders having parts cooperative for timed admission of air from piston to cylinder, means providing driving connection from said 15 cylinders to said crankshaft, a propeller mounted upon said crankshaft forward of said wing, said bulkhead having a mouth for its said passage located in the slip stream of said propeller.
- 15 13. In the wing of an aeroplane, an engine having a crankshaft extending fore and aft of said aeroplane, a fore-and-aft bulkhead having a passage, hollow pistons secured to said bulkhead and disposed upon lateral axes, with the passage of said bulkhead communicating with the cavities of 20 said pistons, a cylinder for each piston, said pistons and cylinders having parts cooperative for timed admission of air from piston to cylinder, means providing driving connection from said 25 cylinders to said crankshaft, a propeller mounted upon said crankshaft forward of said wing, said bulkhead having a mouth for its said passage located in the slip stream of said propeller.
- 20 14. In a wing of an aeroplane, an engine having a plurality of pistons arranged in a row fore and aft of the wing, each upon an axis extending transversely of said plane, a cylinder for each piston movable thereon and having an exhaust pipe, an exhaust manifold extending fore and aft of said wing with an open mouth at the forward 25 portion of the wing and a discharge opening at the rearward part of the wing, said manifold having, for each said exhaust pipe, an opening to receive said pipe and elongated to permit said cylinder movement.
- 25 15. In the wing of an aeroplane, an engine having a stationary piston and a cylinder movable upon said piston, means for supporting said cylinder independent of said piston and comprising a bulkhead for said wing, and rod means connected to said cylinder and having a bearing in said bulkhead.

DAVID J. DOLAN.
